CLAIM

The ornamental design for a mail convenience center, as shown:

DESCRIPTION

FIG. 1 is a top front perspective view of a mail convenience center showing my new design;

FIG. 2 is a front elevation thereof;

FIG. 3 is a top plan view thereof;

FIG. 4 is a side elevation thereof;

FIG. 5 is a side elevation as seen from the opposite of

FIG. 4; and

FIG. 6 is a rear elevation thereof.

—FIG. 1

—FIG. 2

FIG. 3

FIG. 4

—FIG. 5

—FIG. 6
